UNITED STATES PATENT OFFICE.

WILLIAM H. CASTOR AND SAMUEL B. CASTOR, OF WAYNE, COUNTY OF HAMILTON, INDIANA.

GAS-PRESSURE PUMP.

SPECIFICATION forming part of Letters Patent No. 406,261, dated July 2, 1889.

Application filed June 23, 1888. Serial No. 277,997. (No model.)

To all whom it may concern:

Be it known that we, WILLIAM H. CASTOR and SAMUEL B. CASTOR, citizens of the United States, residing in Wayne township, in the 5 county of Hamilton and State of Indiana, have invented certain new and useful Improvements in Gas-Pressure Pumps, of which the following is a specification.

The object of our said invention is to provide a cheap and efficient means for elevating water or other substances by means of natural-gas pressure, as will be hereinafter particularly described and claimed.

Referring to the accompanying drawings, which are made a part hereof, and on which similar letters of reference indicate similar parts, Figure 1 is a side elevation of the apparatus we have devised for this purpose, shown in its operative position in a well; 20 Fig. 2, a central vertical section through a portion of the apparatus, the central portion of which is broken out to enable the parts to be illustrated on a larger scale; Fig. 3, a cross-section on the dotted line 3 3 in Fig. 2; and 25 Fig. 4, a view similar to Fig. 2, showing a modified construction adapted for use with driven wells.

In the accompanying drawings, the portion marked A represents the main body or stock 30 of the pump, and B the gas-supply pipe.

The pump-stock A is preferably a metallic tube, as shown, arranged in the well in the usual manner, and provided on its top with a discharge-spout and on its lower end with a 35 collar provided with a series of tubular set-screws a, extending in toward its center for securing the gas-pipe in position and affording inlet-openings for the water, as will be presently described.

40 The gas-supply pipe B is any suitable pipe connected with the gas-main, or other source of supply, by a connecting-pipe B', and is provided with a valve b in its upper end in a convenient position to be operated for controlling the supply of the gas. It is extended 45 down into the well alongside the pump-stock to the lower end thereof, where it is turned and extended up into said pump-stock a considerable distance, its upper end being beneath the surface of the water. It is consid-

erably smaller than the pump-stock pipe, and is secured centrally therein by means of the tubular set-screws a, which are screwed in against said gas-pipe, and thus secure it rigidly in position. A valve B², consisting, preferably, of a small rod provided with a cap with suitable packing on its under side, is mounted in the upper end of the gas-pipe, and operates to close said upper end when the apparatus is not in use, as will be presently 55 described. A cross-pin or other suitable device a' is mounted within the pump-stock a short distance above this valve to prevent it from being thrown out by the force of the gas.

60 The operation of our invention is as follows: It is first placed in the position in the well, as shown, the gas-pipe being suitably connected with the gas-supply, when it is ready for immediate use. It being desired to 65 put the apparatus in operation, the gas is turned on by means of the valve b, and rushes through said pipe to the top end within the pump, forcing the valve B² off its seat, which permits said gas to escape into the water or other substances which are within the pump-stock above this point. The force of 70 the gas operates to carry the water or other substance upward to the top of the stock and out together with the gas, which passes upward when escaping, and may be carried off into pipes for use, if desired, while the water falls into the receptacle provided. This operation creates the suction necessary to draw 75 in a supply of water from the well through the tubular set-screws a, and the annular opening in the lower end of the pump-stock around the gas-pipe, thus maintaining a continual steady stream of water from the discharge-spout as long as the gas is permitted 80 to flow into the pump. When the supply of water desired has been secured, the valve b is operated to cut off the supply of gas, when the weight of the water above the valve B² carries it down to its seat on the upper end 85 of the gas-pipe B, forming a tight joint and preventing any further escape of gas, or any water from getting into said gas-pipe.

90 The construction shown in Fig. 4 is for use with driven wells, in which case it is impos- 95

sible, on account of the size of the well, to have the gas-pipe extended down on the outside of the tubing. As shown, the gas-pipe is extended into the tubing at the top of the well and down to near the bottom, where its end is mounted in a valve consisting of a short piece of tubing of a larger size, which is provided with a cap, and is secured thereto by a spring, one end of which is attached to 10 said valve and the other to the gas-pipe, and operates to hold said valve, which is provided with suitable packing against the lower end of said gas-pipe. The operation of the gas forces the valve away from the end of the 15 gas-pipe, stretching the spring sufficiently to permit the gas to escape from its lower end through perforations in the lower end of the valve, and also up through the annular space between the valve and gas-pipe, operating to 20 elevate the water in the same manner as with the other form of pump, as will be readily understood.

Having thus fully described our said invention, what we claim as new, and desire to secure by Letters Patent, is—

1. The apparatus for elevating water or a similar substance, consisting of a pipe inserted in a supply of water and another pipe arranged within said first pipe for supplying 25 gas under pressure, its top end being arranged beneath the surface of the water or other substance, and the tubular set-screw a , inserted through said first-mentioned pipe against said last-mentioned pipe, whereby it

is secured in position and water-inlets provided, substantially as set forth. 35

2. The combination, in an apparatus for elevating water, of the pipe A, the lower end of which is inserted in the water-supply, the natural-gas pipe B, inserted in the lower end 40 of said pipe A, and the valve B^2 in the upper end of said pipe B, consisting of a disk of a size to close the end of said pipe mounted on a stem which extends down into said pipe, and the stop a' , arranged above said valve in 45 the pipe A, all substantially as described, and for the purpose specified.

3. The combination of a pipe or stock A, extending beneath the surface of the water or other substance to be elevated, the gas-pipe B, 50 provided with a valve b , and extending up into the lower end of the stock or pipe A, and the valve B^2 , arranged in the top of said pipe B, subject to gas-pressure on the lower side and water-pressure on the upper side, suitable 55 openings being provided at the lower end of the stock or pipe A for the inflow of the substance to be elevated, substantially as set forth.

In witness whereof we have hereunto set 60 our hands and seals at Indianapolis, Indiana, this 19th day of June, A. D. 1888.
